Des. 198,953
Patented Aug. 18, 1964

198,953

BOTTLE CAP

Duane J. Quintal, 32 Gramercy Park S.,
New York 3, N.Y.

Filed Jan. 15, 1964, Ser. No. 78,201

Term of patent 14 years

(Cl. D58—26)

FIG. 2

FIG. 1

FIG. 3

FIG. 4

The portions shown in broken lines are for illustrative purposes only.

I claim:

The ornamental design for a bottle cap, substantially as shown and described.
